HARDY N. BAKER, OF BOSTON, MASSACHUSETTS, ASSIGNOR TO
BENJAMIN D. WASHBURN, OF SAME PLACE.

Design No. 3,228, dated November 10, 1868.

DESIGN FOR A BLIND-HINGE.

The Schedule referred to in these Letters Patent and making part of the same.

Be it known that I, HARDY N. BAKER, of Boston, in the county of Suffolk, and State of Massachusetts, have invented or produced a new and original Design for a Hinge for Blinds, Shutters, &c., of which the following is a full, clear, and exact description, reference being had to the accompanying drawings, making a part of this specification, in which—

Figure 1 represents a plan view of a hinge embodying my invention.

Figure 2 is a side view of the same.

In the drawings, *a* represents the portion of the hinge which is screwed to the blind or shutter. The ends are curved, as shown at *ff*, and are formed with reverse curves, as shown at *d*.

c c represent the screw-holes at the ends, and *c'* that at the centre. The latter is not in line with the

two end holes, but is placed on a line nearer the shank or portion *b* of the hinge than the holes *c c*.

The portions marked *ee*, at the junction of the parts *a* and *b*, are curved, instead of angular, as usually made.

What I claim as new, and desire to secure by Letters Patent, is—

The design for a hinge for blinds, shutters, &c., as set forth and represented.

In testimony whereof, I have signed my name to this specification, in the presence of two subscribing witnesses.

H. N. BAKER.
